UNITED STATES PATENT OFFICE.

ARTHUR EDWARD PEARSON, OF LITTLETON, NEW HAMPSHIRE.

GATHERER.

Application filed October 24, 1921. Serial No. 509,837.

To all whom it may concern:

Be it known that I, ARTHUR E. PEARSON, a citizen of the United States, and resident of Littleton, in the county of Grafton and 5 State of New Hampshire, have invented certain new and useful Improvements in Gatherers, of which the following is a specification.

This invention relates to improvements in 10 gatherers especially adapted for application to sewing machines.

An important object of this invention is to provide a sewing machine gatherer having novel means for gathering the fingers of 15 gloves and other pieces of work so that the same will be in proper position for sewing.

A further object of the invention is to provide a gatherer which may be readily and conveniently applied and which may 20 be thrown to an inoperative position when not in use.

A further object of this invention is to provide a gatherer which is simple to operate, durable in use and cheap to manu- 25 facture.

Other objects and advantages of the invention will be apparent during the course of the following description.

In the accompanying drawing forming a 30 part of this application and in which like numerals are employed to designate like parts throughout the same,

Figure 1 is an edge elevation of the improved gatherer applied.

Figure 2 is a side elevation of the im- 35 proved gatherer applied.

Figure 3 is a perspective of the improved gatherer.

Figure 4 is a perspective of the cam or 40 latch embodied in the invention.

Figure 5 is a perspective of the gatherer bar detached.

Figure 6 is a fragmentary plan view of 45 the plate of the sewing machine, the view illustrating a portion of the gatherer.

In the drawing wherein for the purpose of illustration is shown a preferred embodiment of the invention, the numeral 10 designates the working plate or bed of a sewing 50 machine especially adapted for doing heavy work.

The work plate or bed 10 is provided with the usual opening for the reception of the feed rocker 11 having the usual bar 120 for 55 operating the same. The upper end of the feed rocker 11 is provided with the usual

feed foot which is reciprocated for feeding the material to the proper position with reference to the needle 12 connected by means of a set screw 13 to the needle carrier 14. 60

The invention forming the subject matter of this application is in the nature of a gatherer especially adapted for cooperating with the feed rocker and the foot of the same presenting the material to be sewed to the 65 needle in proper position. The improved gatherer consists of a supporting plate 16 having a plurality of openings 17 for the reception of fastening screws 18 by means of which the supporting plate is secured to 70 the work post 19.

As illustrated particularly in Figure 3 a gatherer bar 20 is arranged at one side of the supporting plate 16 and is slidably secured thereto by means of a pivot element 75 21 extended laterally from the supporting plate and having its terminal portion screw threaded for engagement with an adjusting nut 22. The adjusting nut 22 forms a means whereby the tension of a spring 24 mounted on the pin 21 may be readily and conveniently varied for tensioning the gatherer bar to the desired degree. When the thumb nut 22 is advanced on the pin 21, the tension of the coiled spring 23 will be increased, thereby exerting a spring tension 80 on the gatherer bar 20. On the other hand when it is desired to relieve the tension, the adjusting nut 22 may be backed up for reducing the tension exerted by the coiled 85 spring 23.

The upper portion of the gatherer bar 20 extends through the work bed 10 of the machine and is provided with a longitudinal incision 24 which receives the rear portion 90 of the gathering finger 25. The longitudinal incision 24 provides a pair of arms which may be securely engaged with the attaching portion of the finger 25 by means of a screw bolt 26. The terminal portion of the finger 100 25 is provided along its lower longitudinal edge with a series of teeth 27 adapted to be engaged with the material for gathering the same.

The gatherer bar 20 is rocked by means 105 of a crank 30 having one end portion provided with a laterally projecting pin 31 extended through an elongated slot 33 in the lower portion of the gatherer bar. The other end portion of the crank 30 is provided with a squared pin 34 adapted to be extended 110 through the feed rocker and secured

thereto by means of a nut 35. When the feed rocker 11 of the sewing machine is operated, the crank 30 will also be operated for imparting a rocking or swinging motion 5 to the gatherer bar 20. When the gatherer bar 20 is thus operated, the finger 25 of the same will be engaged with the material mounted upon the bed 10 for gathering the material for subsequent sewing.

10 When the crank 30 operates the gatherer bar 20 in a clockwise direction the gatherer bar is also elevated by contact with a cam 38 pivotally mounted on a pin or stud 39 carried by the base plate 16. More specifically the cam 38 pivotally mounted on the pin 39 is provided with an upwardly extending lobe 40 arranged in the path of travel of the downwardly extending ear 41 on the lower end of the gatherer bar 20. It is thus 15 seen that when the gatherer bar 20 is moved in a counter-clockwise direction the curved face of the depending ear 41 will be engaged with the curved side of the lobe 40 for imparting an upward movement to the gatherer bar and consequently the finger 25 of the same. This upward movement of the gatherer bar takes place simultaneously with the return movement of the gatherer bar at which time the feed is advancing or 20 moving in the opposite direction. The cam 38 is rotatable on the pivot pin 39 and is held thereon by means of a collar 44 having a set screw 45 which engages the pin 39. The pivotal movement of the cam 38 is 25 limited by means of an adjustable stop element 46 arranged in the path of travel of the lobe 40 and adapted to be received within a notch 47 in the lobe.

30 The lobe 40 is urged into engagement with the stop element 46 by a coiled spring 48 having connection with an anchoring post 49 and a depending apertured ear 50, the said ear being formed integral with the cam 38.

45 On the operative stroke of the finger the depending ear 41 of the gatherer bar engages the flat side of the cam 40 and swings the cam on its pivot 39 against the tension of the coiled spring 48.

50 A retaining spring 55 is connected to the anchoring post 49 and to a stud 56 extending from one end of the gatherer bar and the said retaining spring 55 serves as a means for urging the gatherer bar downwardly 55 into engagement with the material and to its operative position. However, the coiled spring 55 permits the gatherer bar to be elevated when the depending ear 41 is engaged with the inclined sides of the cam lobe 40.

60 It will be seen that when the feed rocker moves about the longitudinal axis of the bar 120 the crank 30 will be operated for imparting a rocking motion to the gatherer bar 20. When the gatherer bar 20 is moved

in a counter-clockwise direction it is on the return stroke and is therefore elevated by the engagement of the depending ear 41 with the lobe 40. When the depending ear 41 passes over the lobe 40 the finger 25 70 drops onto the material and the movement of the gatherer bar in a clockwise direction causes the material to be gathered. It is obvious the use of the improved gatherer does not in any way interfere with the operation of the sewing machine and since it is strictly an attachment thereto it may be readily and conveniently removed. However, it is not necessary to entirely remove the gatherer when the same is not in use 75 as the same may be moved to an inoperative position by means of an adjusting rod 60 connected to the gatherer bar by means of an ear or hinge member 61 which incidentally is rotatably connected to the 80 gatherer bar. More particularly the gatherer bar is formed with a longitudinal slot 63 which receives the attaching pin of the ear or hinge member 61.

85 By reason of hingedly connecting the adjusting rod 60 to the gatherer bar the adjusting rod does not in any way interfere with the vertical or rocking motion of the gatherer bar. The adjusting rod may be held in a set position by means of a thumb nut 66 arranged above the plate or bed 10. A hand lever 68 is connected to the adjusting rod 60 and forms a means whereby the gatherer bar may be drawn away from the needle 12.

90 In other words the adjusting rod 60 and the member 20 may be held in a set position by tightening the thumb nut 66. It is thus seen that the gatherer may be positioned out of the way when necessary.

95 Having thus described the invention, what is claimed is:—

1. A gatherer for sewing machines comprising a longitudinally slotted gatherer bar provided with an ear, a cam having a lobe 110 provided with a curved side in the path of travel of said ear and adapted to move the gatherer bar longitudinally, a supporting pin extending through said slot and supporting the gatherer bar for sliding and rocking movement, and a bar tensioning member associated with said supporting pin.

115 2. A gatherer for sewing machines comprising a slotted gatherer bar provided with an ear, a cam having a lobe provided with a curved side in the path of travel of said ear and adapted to move the gatherer bar longitudinally, a pin extending through the slot and supporting the bar for sliding and rocking movement, and means extending 120 through the slot in the gatherer bar to rock the gatherer bar.

125 3. A gatherer for sewing machines comprising a supporting plate, a gatherer bar slidably and rotatably connected thereto,

said gatherer bar being provided with a laterally projecting finger, a crank connected to said gatherer bar and having means whereby the same may be connected to the 5 rocker of a sewing machine, and a cam having a lobe arranged in the path of travel of said gatherer bar whereby to elevate the gatherer bar on its return movement.

4. A gatherer for sewing machines comprising a supporting plate, a gatherer bar slidably and rotatably connected thereto, a crank connected to said gatherer bar and having means whereby the same may be connected to the rocker of a sewing machine, 10 a cam having a lobe arranged in the path of travel of said gatherer bar whereby to elevate the gatherer bar on its return movement, and tensioning means for said gatherer bar.

20 5. A gatherer for sewing machines comprising a gatherer bar having a work engaging finger, the lower portion of the gatherer bar being provided with an ear having a curved side, a cam having a lobe provided 25 with a curved side arranged in the path of travel of said ear whereby the engagement of the curved side of said ear with the curved side of said lobe elevates said gatherer bar, and means to rock said gatherer bar.

30 6. A gatherer for sewing machines comprising a gatherer bar, the lower portion of the gatherer bar being provided with an ear having a curved side, a cam having a lobe provided with a curved side arranged in the 35 path of travel of said ear whereby the engagement of the curved side of said ear with the curved side of said lobe elevates said gatherer bar, means to rock said gatherer bar, and a stop element engaged with said 40 lobe.

7. A gatherer for sewing machines comprising a gatherer bar having a work engaging finger, the lower portion of the gatherer bar being provided with an ear having a 45 curved side, a cam having a lobe provided with a curved side arranged in the path of travel of said ear whereby the engagement of the curved side of said ear with the curved side of said lobe elevates said gatherer bar, 50 means to rock said gatherer bar, a stop element engaged with said lobe, and a spring

urging said lobe into engagement with said stop element.

8. A gatherer for sewing machines comprising a gatherer bar having a work engaging finger, the lower portion of the gatherer bar being provided with an ear having a curved side, a cam having a lobe provided with a curved side arranged in the path of travel of said ear whereby the engagement of the curved side of said ear with the curved side of said lobe elevates said gatherer bar, means to rock said gatherer bar, a stop element engaged with said lobe, a spring urging said lobe into engagement 60 with said stop element, and a spring connected to said gatherer bar for urging the same downwardly.

9. A gatherer for sewing machines comprising a gatherer bar provided with an ear, a cam having a lobe arranged in the path of travel of said ear whereby the engagement of said ear with said lobe elevates said gatherer bar, means to rock said gatherer bar, a stop element engaged with said lobe, 70 a spring urging said lobe into engagement with said stop element, a spring connected to said gatherer bar for urging the same downwardly, and an adjusting member connected to said gatherer bar.

10. A gatherer for sewing machines comprising a supporting plate having a laterally projecting pin, a gatherer bar having an elongated slot receiving said pin, a tensioning spring arranged on said pin, an 80 adjusting nut threaded on said pin and engaging said spring, the upper portion of said gatherer bar being provided with engaging means, a cam rotatably carried by said supporting plate and having a lobe arranged in the path of travel of said gatherer bar whereby the engagement of the gatherer bar with the lobe elevates the gatherer bar, a crank having a laterally projecting pin 85 passed through said elongated slot, said crank also being provided with a feed rocker engaging pin, a spring connected to said gatherer bar for urging the same downwardly, and an adjusting member associated with said gatherer bar.

ARTHUR EDWARD PEARSON.
